(57) **CLAIM**

I claim the ornamental design for a combined keypad and dimmer, as shown and described.

DESCRIPTION

FIG. 1 is a perspective view of a combined keypad and dimmer according to a first embodiment of my design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a combined keypad and dimmer according to a second embodiment of my new design; and,

FIG. 8 is a front view thereof, the left side, right side, top and bottom views, respectively, of the second embodiment being identical to the left side, right side, top and bottom views of the first embodiment.

The rear views form no part of the design and are omitted. The portions of the drawings appearing in broken line are for environment only and do not form a part of the design.
